ATTORNEY

UNITED STATES PATENT OFFICE.

EDWIN C. POWELL, OF MARYSVILLE, CALIFORNIA.

LANDING NET.

Application filed October 15, 1928. Serial No. 312,437.

This invention relates to landing nets for the use of sport fishermen, and particularly to those of the so-called folding or collapsible handle type.

5 The principal object of my invention is to provide a net of this general character in which the handle is so mounted as to be very easily and quickly moved to an extended or folded position without any manipulation 10 of adjusting screws, catches or the like being necessary; and one which is very compact and handy to carry when folded.

A further object of the invention is to produce a simple and inexpensive device and 15 yet one which will be exceedingly effective for the purpose for which it is designed.

These objects I accomplish by means of such structure and relative arrangement of parts as will fully appear by a perusal of 20 the following specification and claims.

In the drawings similar characters of reference indicate corresponding parts in the several views:

Fig. 1 is a perspective view of my improved net showing the handle extended.

Fig. 2 is a similar view showing the handle folded.

Referring now more particularly to the characters of reference on the drawings, the 30 numeral 1 denotes a circular net-rim, formed of a stiff non-corrosive spring wire to which the flexible cord net 2 of common construction is fastened.

At points on its rim close to each other, the 35 wire is formed with a pair of upstanding eyes 3, the openings of which are horizontally aligned and the axes of which openings are disposed in a plane substantially tangent to the rim. Beyond the eyes the wire extends straight and horizontal for a short distance to form substantially parallel extensions 4, the outer ends of which are connected by an upstanding arch 5. The sides of the arch portion adjacent their junction with 45 the horizontal extensions are formed with notches 6 in their opposed outer faces. As will be evident from the above description and showing on the drawing the wire portions are formed from a single piece of wire, 50 the ends of which are preferably in the rim and are brazed or welded together.

The handle member for manipulating the net comprises a U shaped element 7 also of stiff spring wire, whose separated side arms

are provided on their ends with horizontal 55 and oppositely facing eyes 8. These eyes are permanently engaged with the eyes 3 so that the handle is turnably mounted in connection with the net rim for swinging movement in a vertical plane. The space between the side 60 arms of the handle member near the eyes is less than the greatest width of the arch 5 on the outside, which is just above the notches 6. Therefore when the handle is swung from a folded position on the net rim to engage the 65 arch (which is positioned relative to the handle so as to pass between the side arms thereof), said arms must spread before they can pass the above mentioned widest portion of the arch and seat in the notches 6. The 70 adjacent portions of the arms then rest on the extensions 4 and practically form continuations thereof. Since the arms are of spring material and resist a spreading apart movement, it will be seen that when thus 75 disposed the rim extensions and handle are releasably held together so as to form a substantially rigid unit.

When the net is positioned in proper relation to the rim (that is when the handle is 80 uppermost relative thereto) the handle when extended cannot possibly drop below the plane of the rim, since it is supported on the extensions 4 as above stated. Should the user in his excitement however invert the 85 rim and net so that the handle is then above the extensions 4, the parts will still be maintained rigid with each other. This is on account of the spring engagement of the handle arms with the notches, which engagement 90 is aided by the natural compressive grip on the arms exerted by the operator in manipulating the net.

The length of the handle is preferably such that when folded it will extend across 95 the net rim so as to rest on the opposite side thereof, as shown in Fig. 2. The provision of the arch makes the net convenient to carry, since it forms in effect a hook which may be engaged with the belt of the fisherman, the extensions 4 being first passed between the belt and trousers.

From the foregoing description it will be readily seen that I have produced such a device as substantially fulfills the objects 105 of the invention as set forth herein.

While this specification sets forth in detail the present and preferred construction

of the device, still in practice such deviations from such detail may be resorted to as do not form a departure from the spirit of the invention, as defined by the appended 5 claims.

Having thus described my invention what I claim as new and useful and desire to secure by Letters Patent is:

1. A landing net including a net-rim, 10 spaced extensions projecting from one side of the rim, an upstanding arch connecting the outer ends of the extensions, and a handle member comprising spaced arms swivelly mounted in connection with the 15 rim adjacent the extensions, for swinging movement in a plane at right angles to the plane of the rim; said arms resisting separation beyond their normal spacing and such spacing being less than the exterior width at 20 its widest point, the arch having oppositely

facing notches to receive the arms located below said widest point.

2. A landing net including a net-rim, spaced extensions projecting from one side of the rim, an upstanding arch connecting the outer ends of the extensions, upstanding and parallel eyes provided at the junction of said rim and extensions, a handle member comprising spaced arms having eyes at one end swivelly engaged with said first named eyes, and means between the arch and handle member for causing the latter to be releasably held locked in substantial longitudinal alinement with the extensions when said handle is swung over to receive the arch between the arms of the handle. 25 30 35

In testimony whereof I affix my signature.

EDWIN C. POWELL.
